UNITED STATES PATENT OFFICE.

HARRY E. SCHOENHUT, OF PHILADELPHIA, PENNSYLVANIA, ASSIGNOR TO THE A. SCHOENHUT COMPANY, OF PHILADELPHIA, PENNSYLVANIA, A CORPORATION OF PENNSYLVANIA.

DOLL.

1,387,317.

Specification of Letters Patent.

Patented Aug. 9, 1921.

Application filed March 26, 1920. Serial No. 368,863.

To all whom it may concern:

Be it known that I, HARRY E. SCHOENHUT, a citizen of the United States, residing in Philadelphia, Pennsylvania, have invented 5 certain Improvements in Dolls, of which the following is a specification.

One object of my invention is to improve the construction of dolls by making the eyes in a fixed position and providing movable 10 eyelids, which will move to the open position when the doll is erect, and will cover the eyes when the doll is in a recumbent position.

A further object of the invention is to de- 15 sign the doll so that the eyes are carried by a removable section.

A still further object of the invention is to design the doll so that the weighted member carrying the eyelids is pivoted to the re- 20 movable eye section.

In the accompanying drawings:

Figure 1, is a side view of a doll's head, partly in section, the section being taken on the line 1--1, Fig. 4;

25 Fig. 2, is a sectional view on the line 2--2, Fig. 4;

Fig. 3, is a rear view of the head with the back section removed and the eye section also removed;

30 Fig. 4, is a view similar to Fig. 3 with the eye section in place;

Fig. 5, is a sectional view similar to Fig. 2, showing the head when the doll is in a recumbent position;

35 Fig. 6, is a detached perspective view of the eye section;

Fig. 7, is a detached perspective view illustrating the weighted lids;

Fig. 8, is a rear view with the back section 40 removed, showing a modification in which the lid section for each eye is operated independently, and

Fig. 9, is a detached perspective view of 45 one of the eye sections illustrated in Fig. 8, the lid being attached thereto.

Referring to the drawings, 1 is the head of a doll, which, in the present instance, is made of wood. The head is recessed at the back, as at 2. Connecting with this main 50 recess 2 is a deeper recess 3 of the shape clearly shown in Fig. 3, and having eye sockets 5, 5 therein. 4, 4, are the eye openings in the head. The deep recess 3 has a portion 3^a which extends below the sockets 55 to allow a weight to swing freely therein.

6 is an eye section, having a body portion 7 and two cylindrical extensions 8 in the present instance which fit the curved sides of the recess. At the ends of the extensions are ball portions 9 forming the eye balls on 60 which the eyes 10 are indicated in any suitable manner. This eye section is forced into the recess 3 and can be held therein by friction, by a brad, or other suitable fastenings. The eye section, when in position, is stationary, and is so located that there is a space between each socket and a ball as indicated in Fig. 1, and pivoted to the eye section at 65 11 is an eyelid member 12 having a weight 13 and bent portions 14, which form the 70 eyelids so that when the parts are in position, as illustrated in Figs. 1 and 2, the eyelids are raised above the eyes within the sockets 5 and the eyes 10 are exposed through the openings 4, but when the doll is moved 75 to the recumbent position, as in Fig. 5, the weight holds the eyelids in the vertical position so that they cover the eyes.

In Figs. 8 and 9, I have illustrated a modification in which the eye section is made in 80 two disconnected parts 8^a, each fitting a cylindrical recess in the head. Pivoted to each section is the lid section 12^a consisting of a weight 13^a and a lid portion 14^a. In this instance, while the lids are mounted 85 independently, they close simultaneously when the doll is moved into the recumbent position.

The constructions above described are exceedingly simple and are especially adapted 90 for use in connection with heads of dolls made of wood. When the eye section is placed in position, the back section 15 is secured in place covering the recess at the back of the head. If, for any reason, the 95 eyelids will not act properly, all that is necessary is to remove the back section and withdraw the eye section with the lid section attached thereto. The repair can be readily made, or, if necessary, a new lid 100 section can be substituted, and the parts reassembled.

I claim:

1. The combination of a doll's head having a recess at the back, a socket extending 105 from said recess toward the front of the head, said socket having an eye opening at its forward end; an eye section having a ball portion at one end, said ball portion being located in the socket; and a lid be- 110

tween the ball portion and the socket and adapted to move so as to close the eye opening when the doll is in a recumbent position.

2. The combination of a doll's head having a recess at the back; two sockets extending from said recess toward the front of the head, said sockets having eye openings at their forward ends; an eye section having a ball portion adapted to the sockets; and 10 a weighted lid section pivoted to the ball portion of the eye section.

3. The combination of a doll's head having a recess at the back terminating in two sockets spaced apart, and having an eye 15 opening in each socket; an eye section having a body portion fitting the recess and having two extensions; a ball at the end of each

extension forming an eye; and a lid section pivoted to the ball section and consisting of two laterally curved portions forming 20 the lids and a weight connected to said curved portions adapted to swing freely in the recess in the head.

4. The combination of a doll's head having a recess at the back with curved sides; 25 sockets at the end of the recess; an eye opening in each socket; an eye section having a body portion; and two cylindrical extensions fitting the curved sides of the recess in the head, said extensions having eye balls at 30 their outer ends fitting the sockets, and an eyelid section pivoted to the balls and having a weight.

HARRY E. SCHOENHUT.
